UNITED STATES PATENT OFFICE.

ERICH H. LICHTENBERG, OF MILWAUKEE, WISCONSIN, ASSIGNOR TO KOEHRING MACHINE COMPANY, OF MILWAUKEE, WISCONSIN.

DISTRIBUTING MECHANISM FOR CONCRETE-MIXERS.

1,185,416.

Specification of Letters Patent.

Patented May 30, 1916.

Original application filed October 21, 1912, Serial No. 727,017. Divided and this application filed April 21, 1914. Serial No. 833,461.

To all whom it may concern:

Be it known that I, ERICH H. LICHTENBERG, a citizen of the United States, residing at Milwaukee, in the county of Milwaukee and State of Wisconsin, have invented certain new and useful Improvements in Distributing Mechanism for Concrete-Mixers, of which the following is a specification.

10 In United States Letters Patent 1,141,470, issued June 1, 1915, I have described certain concrete distributing apparatus designed especially for use in connection with concrete mixers and which is particularly advantageous for facilitating the laying of concrete in building roads, paving streets, and for similar purposes.

20 This application is a division of the above identified application, being directed to a special form of the apparatus referred to as embodied in said previous application.

25 In the drawings:—Figure 1 is a side view partly broken away showing my distributing apparatus as it is actually used in connection with a concrete mixing machine, dotted lines illustrating the bucket in dumping position. Fig. 2 is a sectional view approximately on the line 2—2 of Fig. 1. Fig. 3 is a perspective view showing more clearly 30 the opening and closing device for the bucket.

35 In the drawings 1 denotes the mixing drum of a mixing machine, the latter including a truck 2 having the upwardly extending framework 7 which is only illustrated in part. Upon this framework 7 are mounted the various parts of the distributing means comprising this invention, and the driving and control mechanisms for said 40 means. The drum 1 has an annular gear ring 4 with which meshes a driving pinion 5 mounted on a shaft 6 which is supported in bearings formed on beams 8 that project from the framework 7. The shaft 6 has a 45 driving bevel gear 9. Supported in bearings on suitable brackets 14 of the framework 7 is a second shaft 12 transverse to the shaft 6 and carrying clutch mechanism controlled by a lever 20. Said clutch mechanism is designed to cause reverse driving of a cable 22, from the shaft 6 and its driving gear 9. Since the particular clutch mechanism or driving connections intermediate the shaft 6 and the cable 22 are

fully set forth in my patent previously referred to and are not material to the improvements hereinafter described in detail, the same will not be set forth at length other than to say that the cable 22 passes around a drum 21 on the shaft 12 from which drum the cable passes upwardly about a drum 23 supported on the axis 24 at the upper portion of the framework 7. From the drum 23 the cable 22 passes downward beneath a pulley 36 on the bracket 41 which is rigidly attached to the inner end of a long boom 30. From thence the cable extends longitudinally of the boom around a pulley 39 on the outer end of said boom, beneath the boom back toward the inner end of the latter, and upward between pulleys 37 and 38 on the bracket 41 back to the drum 23. The boom 30 is preferably mounted to swing about a vertical axis carried by an offstanding bracket 28 on the framework 7, 75 and a hand wheel 34, its shaft 33, and the toothed segment 31 are instrumentalities utilized for turning the boom on its pivot or axis, the segment 31 engaging a worm, not shown, on the shaft 33. Any suitable 80 means, however, may be employed for shifting the boom horizontally within the purview of the invention, and any means equivalent to the cable 22 may obviously be used.

85 The boom 30 is preferably an I-beam and therefore has channels at its opposite sides. A carriage 47 having supporting rollers 48 operating in the channels of the boom 30 at opposite sides thereof, is thus mounted to 90 move longitudinally of the boom 30 and certain peculiarly novel connections intermediate the carriage 47 and the cable 22, are provided as will now be set forth.

95 The carriage 47 supports a bucket 50 arranged beneath the same and connected thereto by hangers 49. A shaft 51 is mounted in suitable bearings on and transversely of the carriage 47. The doors 50' of the bucket 50 are connected by cables 53' with 100 curved links 54' whose upper ends are secured pivotally to laterally extending bosses 55' projecting from the free ends of crank arms 52'. The arms 52' are fixedly secured to the shaft 51, one end of which carries 105 the fixed trip arm 56, the latter having a boss 58 movable with the carriage in a path intersected by a tripping cam 59. The arm

56 is provided with an operating handle 57 which handle might be grasped not only for opening and closing the doors 50 by proper manipulation, but also utilized as a convenient means for swinging the boom 30 horizontally, in the event the mechanism comprising the parts 34, 33 and 31 should be dispensed with. A tripping finger 85 is integrally formed with the lower ends of 10 the arms 52', and is bifurcated to facilitate the connection at the bifurcated portion, see Fig. 2, of short links 86 which are interposed in the length of the cable 22 at the point where the cable passes through the 15 carriage, the links being virtually a continuation of the cable, for all practical purposes.

The discharge of the mixture in the drum 1, into the bucket 50 is controlled by a lever 20 90 and the mixed material passes into the bucket through a chute 3 on the framework 7. Assuming now that under the control of the lever 20 the cable 22 may be moved in reverse directions, it will be apparent 25 that with the parts as arranged in the full line positions in Fig. 1 a movement of the lever 20 will cause the lower bight of the cable 22 to travel outward. The cable 22 is connected with the carriage 47' through 30 the medium of the parts 86, 85, 52' and 51, and therefore the said movement of the cable will forcibly move the carriage 47' and the loaded bucket 50 toward the outer end of the boom 30 to its dumping position. 35 The bucket is dumped under the control of the operator manipulating the lever 20 to cause a reversal of the movement of the cable 22. Such action in effect momentarily discontinues the movement of the cable 22 40 while the carriage 47' and the bucket continue to move a slight distance, this relative movement of the cable and carriage causing the connection 86 and the arms 52' previously disposed at the right side of the axis 51 as seen in Fig. 1, to be moved to the left 45 side of said axis as shown in the dotted lines in Fig. 1, whereby the arms 52' and the links 54' move downward a sufficient distance to permit the doors 50' of the bucket 50 to completely open. When the doors 50' are 50 in open positions (see dotted lines Fig. 1) the trip arm 56 will have been moved so as to incline leftward in respect to the axis 51. The movement of the arm 56 as well as the arms 52' is limited by the provision of a stop 52" 55 in the form of a lug integral with the arms 52', there being formed on the carriage 47' a pin or equivalent member 52a adapted to engage the stop 52" for the purpose just referred to.

As above suggested, the reversal of the movement of the cable 22 is effective to cause the dumping of the bucket 50 and practically as soon as the dumping takes place 60 the continued movement of the cable 22 in

the reversed direction mentioned causes the carriage and the bucket to travel toward the inner end of the boom in an obvious manner. As the carriage approaches the limit of its inward movement on the boom 30 the boss 70 58 of the arm 56 is engaged by the tripping or restoring cam 59 which thereby rocks the shaft 51 and normalizes the parts 52', 53' and 50', the bucket 50 being then ready to receive another charge at the will of the operator. 75

In so far as the general operation of the machine as above described is concerned, the same is quite similar to the general principle of operation of my machine as illustrated and claimed in the Letters Patent 80 previously referred to. However, the machine as claimed hereinafter is designed to operate on what I believe to be a generally new principle of action in the art, such operation, however, being less preferred than 85 that hereinbefore set forth, owing to the fact that the operator of the machine is required to be more skilful in respect particularly to the controlling of the closing of the bucket, than if the closing cam device 59 is utilized 90 wholly for effecting the automatic normalizing of the bucket. The principle of operation just mentioned resides in the peculiar combinative action of the parts incident to the permanent connection of the cable 95 22 with the pivoted member which comprises the arms 52', the finger 85 integral therewith, and the stop 52" also integral with said arms. It must be remembered that this pivoted member is a trip means 100 in the form of a bucket opening and closing device, generally speaking, owing to its operation with the doors of the bucket.

The manner of discharging the bucket has been previously described, being incident to the reversal or stopping of the cable 22 during the outward movement of the carriage as the bucket reaches the discharge position, the action of the cable being to shift the parts 85 and 52' sufficiently to 105 lower the links 54' and open the doors of the bucket. Now it is possible to close the bucket without employing the coöperation of the cam 59 with the boss 58 of the arm 56. Supposing the parts to be in the dotted 110 line positions shown in Fig. 1, it will be evident that movement of the lower bight of the cable 22 toward the mixing machine will cause the carriage 47' and the bucket to move toward the drum 1 likewise, as required preliminary to recharging. If during the inward movement of the carriage 47' and the bucket 50, and approximately 115 at such time as the carriage 47' reaches a position adjacent to the inner end of the boom, the operator by actuation of the clutch controlling lever 20 stops or momentarily reverses the cable 22 the momentum of the carriage 47' and the bucket 50 will cause 120 these parts to move slightly and sufficiently 125

65 the continued movement of the cable 22 in

- to exert an outward pull on the parts 85 and 52' whereby to throw the arms 52' over the dead center, and thus lift the doors 50' to their closed positions in respect to the 5 bucket. While as suggested above the employment of the cable 22 as the sole means to open the bucket and close the same, effectuated by causing reverse relative movements of the cable and carriage 47', is not 10 ordinarily used in preference to the tripping action of the cam 59 acting on the arm 56 owing to the requirement of nicety of judgment of the operator, still such operation is entirely practicable and may be 15 sorted to when desired according to the conditions of service of the machine.
- So far as I am advised the operation of parts as above contemplated wherein there is provided a bucket closing and opening 20 device on the carriage connected with the cable whereby the carriage and bucket may be moved back and forth along the boom, and operable initially to discharge the contents of the bucket incident to relative movement of the cable and carriage, and operable 25 subsequently by additional relative movement of the cable and the carriage to close the bucket, or restore it to its normal condition, is broadly new.
- 30 Means such as a winding shaft and its actuating wheel 84 together with the cable 79 passing about the pulley 78 may be utilized for raising and lowering the boom 30. Any means equivalent to these means 35 may be employed, however.
- Having thus described the invention, what is claimed as new is:
1. In a distributing machine, the combination of a support, a carriage adapted to travel along said support, a cable operable in reverse directions to impart corresponding movement to the carriage, a bucket supported by the carriage, a rock shaft on the carriage, a bucket closing and opening member on said shaft, a connection intermediate said cable and the bucket closing and opening member by which the cable may move the carriage, and controlling means for the cable for effecting initial relative movement 40 of the same in respect to the carriage to act through said connection to open the bucket, and said connection including an element causing said opening and closing member to act to close the bucket on subsequent relative movement of the cable and carriage, and stop means coacting with the closing and opening member to limit its movement relatively to the carriage.
  2. In a concrete distributing machine, the combination of a boom, a carriage adapted to travel back and forth on the boom, a bucket supported by said carriage, dumping doors for said bucket, a reversely operable cable associated with the boom to actuate the carriage, a pivoted member mount- 45 ed on the carriage, a permanent connection between said pivoted member and the doors of the bucket to hold the latter in closed positions, an operating connection between the cable and said pivoted member for imparting movement of the cable to the carriage and including means which on predetermined relative movements of the cable and carriage actuate the said pivoted member to open and close the bucket doors.
  3. In a concrete distributing machine, the combination of a boom, a carriage and bucket supported thereby adapted to move along said boom, dumping doors for the bucket, an arm pivoted on the carriage and connected with the doors of the bucket to open and close the latter and normally positioned so as to lock the doors closed, a tripping finger projecting from said arm, a cable associated with the boom, an operating connection between said cable and the carriage whereby to move the latter along the boom with the bucket, said operating connection comprising means directly engageable with said tripping finger to shift the arm from a position holding the bucket doors closed to a position wherein said doors are opened, and said connection including an element directly engaging said tripping finger to restore the doors of the bucket to closed position incident to operation of the cable.
  4. In means of the class described, the combination of a support, a carriage adapted to travel along said support, a cable operable in reverse directions to impart a corresponding movement to the carriage, a bucket supported by the carriage, a shaft on the carriage, bucket closing and opening means on said shaft, and a connection intermediate said cable and the bucket closing and opening means for shifting the latter to actuate the same, and establishing an operative connection intermediate the cable and the carriage to positively move the latter back and forth, said connection comprising a member connected with said shaft and pivotally movable on the carriage to a position in which it locks the bucket closed independently of the action of the cable and attached to the cable at a suitable point in the length of the latter, so as to be shifted by the cable to operate said shaft and discharge the bucket.
  5. In means of the class described, the combination of a boom, a carriage adapted to travel on said boom, a reversely operable driving cable associated with the boom for moving the carriage in opposite directions, a bucket supported by the carriage, a rock shaft on the carriage, trip arms extending from said shaft, dumping doors for the bucket, links connecting said trip arms with the dumping doors and arranged so that when their point with connection of the trip

arms is at one side of the axis of said arm the doors are maintained closed, a permanent connection between the shaft and the cable movable relatively to and independently of the movement of carriage to force said point of connection of the links and trip arms to the opposite side of the axis of said arms whereby to permit opening movement of the doors of the bucket, and stop means to limit the movement of the trip arms.

6. In means of the class described, the combination of a boom, a carriage adapted to travel back and forth on the boom, a bucket supported by said carriage, dumping doors for said bucket, a cable positively movable in reverse directions associated with the boom to actuate the carriage, a pivoted member mounted on the carriage, a permanent connection between said pivoted member and the doors of the bucket to hold the latter in closed positions, a permanent connection between the cable and said pivoted member for imparting movement of the cable to the carriage and adapted on relative movement of the cable and carriage to effect positive movement of said pivoted member to permit opening of the bucket doors, a stop on the pivoted member, and means on the carriage to coact with the stop to thus limit certain movement of said member.

7. In means of the class described, the combination of a boom, a carriage adapted to travel back and forth on the boom, a bucket supported by said carriage, dumping doors for said bucket, a reversely operable cable associated with the boom to actuate the carriage, a pivoted door closing and locking member mounted on the carriage, a permanent connection between said pivoted member and the doors of the bucket to hold the latter locked in closed positions independently of the cable, and means including a permanent connection between the cable and said member for imparting the movement of the cable to the carriage and adapted on relative movement of the cable and carriage to effect movement of said member to permit opening of the bucket doors, and means for restoring said pivoted member to its door closing and locking position.

8. In a distributing machine, the combination of a support, a carriage adapted to travel along said support, a cable positively operable in reverse directions to impart corresponding movement to the carriage, a bucket supported by the carriage, a shaft on the carriage, a bucket closing and opening member on said shaft, and adapted to hold the bucket closed independently of the cable, a connection intermediate said cable and the bucket closing and opening member by which the cable may move the carriage,

and controlling means for the cable for effecting initial relative movement of the same in respect to the carriage to act through said connection to open the bucket, and said connection including an element 70 which on subsequent relative movement of the cable and carriage causes said opening and closing member to close the bucket.

9. In a concrete distributing machine, the combination of a boom, a carriage 75 adapted to travel back and forth on the boom, a bucket supported by said carriage, dumping doors for said bucket, a reversely operable cable associated with the boom to actuate the carriage, a pivoted member 80 mounted on the carriage and normally locking the doors closed independently of the cable, a permanent connection between said pivoted member and the doors of the bucket to hold the latter in closed positions, 85 a permanent connection between the cable and said pivoted member for imparting movement of the cable to the carriage and adapted on predetermined relative movements of the cable and carriage to actuate 90 the said pivoted member to open and close the bucket doors.

10. In concrete distributing apparatus, the combination of a boom, a carriage adapted to move back and forth on the 95 boom, a dumping bucket supported by the carriage, a bucket dumping and restoring member mounted on the carriage, an operating cable, and a connection between the cable and the dumping and restoring member to move the carriage on the boom as the cable is operated, and means to operate said cable for positively tensioning the same preliminarily to cause coaction of the said connection and the dumping and restoring member to dump the bucket, and to operate the cable subsequently to cause coaction of the connection with said member whereby to restore the bucket to charging condition. 100

11. In a concrete distributing machine, 110 the combination of a boom, a carriage adapted to travel along the boom, a bucket supported by the carriage, and means controlling the shifting of the carriage and bucket and the operation of the bucket 115 itself including the following instrumentalities: a bucket closing and opening member associated with the carriage, a reversely operable cable and a positive operating connection intermediate said cable and closing 120 and opening member, and means for placing the cable under tension whereby to actuate the cable to shift said positive connection in one way to cause the dumping of the bucket, and to shift said connection in another way to effect restoration of the bucket to normal condition. 125

12. In a machine for distributing mixed materials for making pavements, the combination with a boom, of a carriage mov- 130

able along the same a distributing bucket sustained by the carriage, dumping and restoring mechanism on the carriage coacting with the bucket to normally hold the latter in a charging condition, an operating cable 5 in a charging condition, an operating cable for moving the carriage back and forth on the boom, a positive connection intermediate the cable and the said dumping and restoring mechanism whereby movement of 10 the carriage on the boom is controlled, and operable to effect dumping of the bucket at will during movement of the bucket and leaving said dumping and restoring mecha- nism in a condition to be normalized, and means to operate said dumping and restoring mechanism by means of the cable and said positive operating connection to restore the bucket to its charging condition after a dumping operation.

In testimony whereof I affix my signature 15 in presence of two witnesses.

Corrections in Letters Patent No. 1,185,416.

It is hereby certified that in Letters Patent No. 1,185,416, granted May 30, 1916, upon the application of Erich H. Lichtenberg, of Milwaukee, Wisconsin, for an improvement in "Distributing Mechanism for Concrete-Mixers," errors appear in the printed specification requiring correction as follows: Page 2, line 95, after the word "permanent" insert the words *and also floating*; page 4, line 51, claim 7, strike out the word "means"; and that the said Letters Patent should be read with these corrections therein that the same may conform to the record of the case in the Patent Office.

Signed and sealed this 25th day of July, A. D., 1916.

[SEAL.]
